UNITED STATES PATENT OFFICE

FRIEDRICH WILHELM CORSALLI, OF BERLIN, GERMANY

DEVICE FOR THE REFINING, MIXING, AND PURIFYING OF MOLTEN METALS AND METAL ALLOYS

Application filed July 23, 1927, Serial No. 207,999, and in Germany June 30, 1926.

Metals melted down in shaft furnaces are, as is known imperfectly mixed and must first be freed from impurities for example: sulphur phosphorous and like substances which favour the formation of gases forming bad castings. The present invention has for its subject matter an apparatus whereby the molten metal or alloy, preferably iron, obtained from a smelting furnace more particularly a cupola furnace, before being cast is subjected to prolonged movements and agitation, it being thus thoroughly mixed and freed from impurities.

The apparatus consists of a receiver provided with actuating means which impart to it, for example, oscillatory, rocking, jarring, rotary or other movements, however, free falling movements liable to cause shock to the foundations of the apparatus, of the furnaces and the buildings are excluded by the invention. The movement of the receiver has solely effect directly upon the metal contents, causing prolonged agitation thereof, without otherwise acting injuriously upon adjacent parts. The receiver may be made in a variety of forms, for example, in the form of a fore-hearth if it is to be placed immediately in front of the smelting furnace.

According to the invention the receiver may be employed separately or in conjunction with a mixer of any kind, placed operatively in front of the receiver and receiving similar movements through actuating means separately or in common with the receiver. The mixer may be arranged independently of the receiver or it may be rigidly connected therewith, preferably the latter, in which case both receive the same motion from common actuating means.

In the event of the receiver being for example placed in the manner of a fore-hearth in front of the smelting receiving directly therefrom the smelted metal for the purpose of purification and refining, the mixer may be so arranged between the receiver and the furnace as to serve as a feeder of the metal to the receiver. The flow motion within the mixer may be utilized by means of suitable guides to effect thorough mixing, prior to the metal entering the receiver. On its passage

through the mixer the metal receives the requisite quantities of refining substances such as carbon, alloys, purification and reaction substances, which owing to the violent motion and splitting up of the metal thoroughly dissolves therein. Further the flow of the metal within the mixer may be utilized for splitting up and mixing the mass of molten metal by appropriately forming the mixer to constitute a system of channels extending to and fro, or branched, or varying in cross section, through which channels the metal is constrained to pass.

The mixer as well as the heater may be equipped with heating means of known kind in order to impart heat to the metal and to retain its temperature at a prolonged period at the temperature at which it left the smelting furnace or if required to impart super-heat thereto. Heating during the period of agitation is effected by known means primarily by means of flue gases from the smelting furnace which are led through the mixer and/or receiver. Alternatively the heating may be effected by electricity, oil-burners, pulverized coal-firing or the like, if conditions be favourable thereto, also by means of pre-heated air. The auxiliary heating can also be effected by the addition of heat-evolving substances such as thermit. The concomitant heating or agitation of the metal in accordance with the invention has the advantage that intermixture is aided and release of gases expedited.

The drawing illustrates diagrammatically in long-sections, the apparatus according to the invention by way of example, Fig. 1 being a vertical longitudinal section, while Fig. 2 is a horizontal section on line II-II of Fig. 1. The apparatus consists of a lower receiver 2 with upper mixer 1. The whole apparatus rests with bosses 3 upon wooden blocks 4 and when in operation is alternately raised and lowered by means of uniformly rotating cam disks 5 which act against noses or abutments 6 on the bottom of the vessel 2, thus producing a pronounced rising or wave-like overthrow motion of the metal contents being produced in measure with the magnitude and frequency of the said movements. Conse-

quently the whole mass of metal is thoroughly mixed, gases and impurities being separated.

The liquid metal enters at the apertures 7 into the mixer, flows in succession through the obliquely disposed channels 8 and passes at the bottom at 9 into the receiver 2. The larger channels 8 are in communication with each other by means of smaller connecting channels, the metal being thus constrained to pass alternately through large and small cross sections. The heating of the apparatus illustrated diagrammatically in the drawing, is effected by flue gases or other hot gases entering through the conduit 62 into the receiver 2, passing through it and imparting heat to the metal contents, whereupon they are led through a by-pass 61 at the other end to the upper portion of the mixer where they pass through the channels 8 and their connecting channels in contrary direction to the entering metal, towards the outlet 27 under the stationary up-take 28. A portion of the heating gases from the conduit 62 enters directly through the aperture 9 into the lower channels 8 of the mixer, traversing the entire mixer, and escaping at the outlet also through the up-take 28. Both parts of the apparatus may be employed in conjunction or either of them without the other and appropriately the receiver may be employed in place of a fore-hearth.

Claims:

1. Apparatus for refining, mixing and purifying molten metals and metal alloys, comprising, a mixer adapted to receive molten metal, a receptacle connected with said mixer, channels in said mixer, the molten metal being mixed in the passage thereof through said channels, and a common actuating means for imparting an oscillating movement to said mixer and receptacle.
2. Apparatus for refining, mixing and purifying molten metals and metal alloys comprising a mixer adapted to receive molten metal, a receptacle rigidly connected with said mixer, means for the passage of molten metal from said mixer to said receptacle, a passage adapted to lead hot gases into said receptacle, a by-pass for returning said hot gases to the mixer in a direction contrary to the flow of the metal, and a common actuating means for imparting an oscillating movement to said mixer and receptacle.
